UNITED STATES PATENT OFFICE.

FRIEDRICH GOLDSCHEIDER, OF VIENNA, AUSTRIA-HUNGARY.

DESIGN FOR A STATUETTE.

SPECIFICATION forming part of Design No. 29,358, dated September 20, 1898.

Application filed May 13, 1898. Serial No. 680,646. Term of patent 3¹/₂ years.

To all whom it may concern:

Be it known that I, FRIEDRICH GOLDSCHEIDER, a subject of the Emperor of Austria-Hungary, and a resident of the city of Vienna, in the Empire of Austria-Hungary, have invented and produced a certain new and original Design for Statuettes, of which the following is a specification, reference being had to the accompanying drawing, forming a part thereof.

10 As shown in the accompanying drawing, the statuette which I claim as my invention represents a negro seated in a bamboo chair smoking a cigarette and busily engaged reading a newspaper. This statuette is modeled in terra-cotta and is made in two sizes, one size being

15 seventy-one centimeters (nearly twenty-four inches) in height, and the other size being one

hundred and fifty centimeters (a little more than fifty-nine inches) in height.

The drawing which accompanies this specification represents correctly and minutely the statuette as it appears in the two sizes modeled in terra-cotta.

Having described my invention, what I claim is—

The design for a statuette, or similar article, as herein shown and described.

In testimony whereof I have affixed my signature in presence of two witnesses.

FRIEDRICH GOLDSCHEIDER.
